UNITED STATES PATENT OFFICE.

WILLIAM H. LARRISON, OF FLORENCE, NEW JERSEY, ASSIGNOR OF ONE-HALF TO WILLIAM F. THACHER, OF FLORENCE, NEW JERSEY.

COLLAPSIBLE CORE-SPINDLE.

SPECIFICATION forming part of Letters Patent No. 766,765, dated August 2, 1904.

Application filed January 2, 1904. Serial No. 187,490. (No model.)

To all whom it may concern:

Be it known that I, WILLIAM H. LARRISON, a citizen of the United States, and a resident of Florence, Burlington county, New Jersey, 5 have invented certain Improvements in Collapsible Core-Spindles, of which the following is a specification.

My invention relates to certain improvements in core-spindles particularly designed 10 to receive a covering of sand or plastic material for use in connection with a suitable mold for the formation of a casting.

The object of the invention is to provide a core-spindle especially adapted for use in the 15 manufacture of pipe or similar tubular articles which shall be of such construction as to be quickly and easily made of a smaller diameter, so as to permit of its removal from a casting.

20 A further object of the invention is to provide a collapsible core-spindle whose operating parts shall be few in number and substantial in construction and which are so arranged that the pressure exerted upon the device by 25 the cooling of the metal of a casting will not in any way alter their adjustment. It is also desired to provide a collapsible core-spindle having its surface composed of a number of sections which shall be independently adjustable under certain conditions of operation.

These objects I attain as hereinafter set forth, reference being had to the accompanying drawings, in which—

Figure 1 is a longitudinal sectional elevation of my improved collapsible core-spindle, 35 illustrating the detail construction of its component parts. Fig. 2 is a transverse sectional elevation of one end of my improved spindle. Fig. 3 is an elevation of the end of the spindle opposite to that shown in Fig. 2, a portion 40 thereof being removed for the sake of clearness. Fig. 4 is a side elevation of the end portion of the improved spindle shown in Fig. 3, one of the staves of the spindle being removed to better illustrate the detail construction; and Figs. 5 and 6 are sectional elevations of portions of my improved spindle, showing a modified construction thereof.

In the above drawings, A represents the

supporting spindle or shaft for my core-spindle, and this has keyed to it or otherwise fixed in position near its ends two head-pieces B and C, which are preferably circular in form, it being noted that I do not limit myself to any particular number of said head-pieces. 50 Extending between the heads in such manner as to inclose the head C are any number of body-sections or staves D, which are provided with flanged portions d at the ends adjacent to the head B. These flanged portions or 55 flanges may be external, as shown in Fig. 1, or internal, as shown at d' in Fig. 5, for the reception of U-shaped clamps b, which extend in one case through a groove in the periphery of the head B or in the other case through an 60 opening in the body of said head in such manner as to hold together the body-sections and the head, it being thus possible to draw such parts together with any desired force by means of a wedge b', inserted between the head 65 B and one of the arms of the clamp.

Each of the body-sections D has bolted to it one or more projecting lugs d², which preferably extend beyond the plane of the ends of said sections in lines at an angle to the axis 75 of the spindle. The head B is provided with correspondingly-shaped openings, as indicated in Figs. 1 and 2, for the reception of said lugs, and each opening is made of such dimensions as to permit the insertion of a wedge between 80 its walls and the lug projecting therethrough, as indicated at d².

The openings through the head B are, like the ends of the projecting lugs d², inclined at an angle to the axis of the spindle, so that it will 85 be seen that inward movement of a lug through the head B not only moves its attached body-section or stave longitudinally, but also moves the same toward or from the spindle A.

In addition to the lugs d² there are on each 90 body-section one or more lugs d⁴, which are also removably bolted in position and project from the inner surface of their supporting-sections at the same angle to the spindle A as that made by the similar portions of the lugs 95 b². For the purpose of accommodating this second set of lugs the head C is made in two parts c and c'. The first of these, c', is conical

in form and has in its external surface dovetailed slots or recesses c^3 , as shown in Fig. 3, and I form the ends of the lugs d^4 of a corresponding shape. In addition to being dovetailed these recesses are wider toward the apex of the conical surface in which they are formed than they are at the base of said surface, so that it will be seen that the correspondingly-shaped lugs d^4 can be moved but a limited distance through them. The portion c' of the head C has a flanged portion c^3 , which encircles the conical surface of the part c and is preferably made so as to engage the lugs d^4 and force them inwardly when they are moved through the recesses in the part C.

Any desired form of screw or bolts c^7 may be employed to retain the two parts c and c' together. There are ribs d^5 formed on the external surface of the staves or body portions D for the purpose of better holding the sand or clay, and it will be understood that said staves fit together in such a manner as to form a substantially cylindrical core-spindle.

In preparing my improved device for use each of the body-sections or staves is moved toward the head B until further motion is stopped by the engagement of the large ends of the lugs d^4 with the sides of the tapered dovetailed slots in the portion c of the head C. Each stave is then permanently retained in position by means of the clamp b or the wedge d^3 , or both, after which the sand or other core-forming substance is molded upon the outside surface of the staves. After suitable drying the finished core is placed in a mold and metal cast upon it, and when said metal is sufficiently cooled the removal of the clamps and wedges leaves the core-spindle in condition to be collapsed or made smaller in diameter. This is accomplished either by moving the spindle A and its heads relatively to the casting and the staves D or by forcing the lugs d^2 through the head B one at a time, in any case freeing them from the casting and permitting easy withdrawal of the core-spindle. It will be noted that the drawing in of the ends of the staves connected to the head C is due to the action of the flanged portion of the part c upon the lugs d^4 . This ability to slack off and move inwardly or outwardly one of the body-sections at a time is a very material advantage, since, particularly in large work, it is practically impossible to move them all simultaneously and lock them rigidly.

It will be understood that in practice both the staves and the heads of my improved core are provided with a large number of perforations for the escape of gas; but for the sake of clearness these have not been shown in the drawings, since they in no way affect the present invention and relate solely to a construction well known to the art. It will be further understood that when moving one of the staves, for example, so as to bring it further from the spindle A the end thereof hav-

ing the lug d^4 is first brought to a fixed position, after which the lug d^2 is fixed relatively to the head B by means of the wedge d^3 .

If desired, the lugs d^2 may be replaced by a construction similar to that shown in Fig. 6, in which b^5 represents a metallic piece fastened to the outside of a stave D and extending through a groove in the edge of the head B. The end of the piece is turned over and bent at an angle, so as to enter the angularly-placed opening in said head, there being a wedge d^6 by which it may be moved, so as to draw the end of the stave to which it is attached toward the head.

I claim as my invention—

1. In a collapsible core-spindle the combination of a supporting-shaft having heads, staves having means whereby their longitudinal motion in one direction also causes them to move in a line radial to the shaft, with means for retaining them in their most distant position from the shaft, said staves being adjustable independently of each other, substantially as described.

2. The combination of a shaft having heads provided with recesses, a series of staves forming a substantially cylindrical body, each stave having a projecting flange extending substantially at right angles to its length, pieces inclined to the line of the shaft and fixed to the staves, said pieces being operative in the recesses of the heads, and a series of independent clamps placed to respectively connect the flanges of the staves and one of the heads on the shaft, substantially as described.

3. The combination of a shaft having heads, one of said heads having dovetailed and tapering recesses, a series of staves having means whereby they are operatively connected to the heads, said means including projecting lugs shaped to coöperate with the dovetailed recesses in one of the heads, substantially as described.

4. The combination of a shaft having recessed heads, a series of staves forming a cylindrical core, means whereby each of the staves is movably held to one of the heads and a lug on each stave engaging a recessed portion of another head, with means for retaining said lug in any desired position relatively to said latter head, substantially as described.

5. The combination in a collapsible core-spindle of a shaft having heads, staves forming a cylindrical body having means in engagement with said heads for causing said staves to be moved toward or from the shaft when they are moved longitudinally, said means including a tapering lug fixed to each stave, there being a correspondingly-tapered recess for said lug in the head adjacent thereto, substantially as described.

6. In a collapsible core-spindle, the combination of a shaft having heads each provided with recesses extending in lines inclined to the line of the shaft, staves forming a cylindrical

body and each provided with a lug for engagement with an inclined recess in each head, certain of said lugs being tapered and others being parallel-sided, with means for retaining 5 said parallel-sided lugs in a fixed position relatively to the head with which they engage, substantially as described.

7. The combination of a shaft having heads, with a series of staves forming a cylindrical 10 core, each of said staves having means in engagement with the heads for maintaining it parallel to the shaft when it is moved longitudinally, said means being constructed to permit the staves to be at different distances 15 from said shaft, with flanges on the staves and independent means for holding each stave to one of the heads, substantially as described.

8. The combination of a shaft having heads provided with inclined recesses, flanged staves 20 forming a cylindrical body and provided with inclined portions for engaging the recesses of the heads, certain of said inclined portions having means for limiting their longitudinal motion relatively to one of the heads, and 25 clamps for engaging the flanges of the staves and holding them to the other one of the heads, substantially as described.

9. The combination of a shaft having heads, a series of staves forming a cylindrical body, 30 lugs having inclined portions in engagement with similarly-formed recesses in one of the heads, another head being formed in two parts, one of the same being substantially conical in form and having recesses in its conical surface, lugs on the staves formed to engage said 35 recesses, another portion of said head fitting around the conical surface of said first portion so as to retain the lugs therein, substantially as described.

10. The combination of a shaft having heads 40 fitted to it, a cylindrical body consisting of a number of independent sections, said sections having fixed to them pieces inclined to the shaft and placed to enter correspondingly-inclined recesses in the heads, the recesses in 45 one of the heads being dovetailed and tapered and the pieces on the staves adjacent thereto being of a similar shape, substantially as described.

11. The combination of a shaft having heads 50 provided with recesses inclined to said shaft, staves having portions also inclined to the shaft and coacting with the recesses, means on certain of the projections of the staves for limiting their motion relatively to the head 55 adjacent thereto, there being recesses in another head larger than the pieces coacting with them and wedges for said recesses for retaining the pieces acting therein in any desired position, substantially as described. 60

12. The combination in a collapsible core-spindle of a substantially cylindrical body consisting of a series of sections, and means for simultaneously moving said sections toward the axis of said body so as to diminish the diameter of the cylinder formed by them, said means permitting outward motion of each section independently of the others, with means for independently holding each section in any adjusted position, substantially as described. 65

In testimony whereof I have signed my name to this specification in the presence of two subscribing witnesses.
